UNITED STATES PATENT OFFICE

HENRY B. GREENWOOD, OF GLENARM, MARYLAND, ASSIGNOR TO F. X. HOOPER COMPANY, INC., OF GLENARM, MARYLAND, A CORPORATION OF MARYLAND

STACKER FOR BOX BLANKS

Application filed August 27, 1930. Serial No. 478,232.

This invention relates to a machine designed to automatically stack box blanks of paper board as they issue from machines which operate upon the blanks, such as a slotting and creasing machine. The stacker of my invention is preferably constructed as a portable unit which may be placed at the delivery end of a slotting and creasing machine and which is provided with its own motor so that it is unnecessary to gear it to the machine.

The stacker comprises a belt conveyor having a front horizontal stretch on to which the blanks are delivered by the machine which operates upon them, and having a rear horizontal stretch traveling in the same direction as the front stretch but in a plane slightly higher than that of the front stretch. The blanks pass between rolls at the rear ends of the front stretch and are forced edgewise against an upwardly traveling part of the conveyor at the front end of the rear stretch and are carried on to the rear stretch. An adjustable stop plate arranged over the rear stretch arrests the movement of each blank before it has passed completely on to the horizontal portion of said stretch, so that the rear portion of the arrested blank overhangs said upwardly traveling part and overlaps the forward part of a succeeding blank when the latter reaches said upwardly traveling part. In consequence the succeeding blank, in passing on to the rear stretch, lifts the rear portion of the arrested blank and is carried under it to the stop. Thus the stack is built up by the successive blanks entering at the bottom of the stack.

In the drawing the stacking machine is shown in longitudinal vertical section. Referring to the drawing A represents the machine as a whole, comprising a frame *a* which is preferably mounted on casters 1 so that it can be moved about as a unit and placed at the delivery end of any machine which operates upon the blanks. In the drawing *b* and *b'* indicate conventionally the slotting heads of a slotting machine, and the stacking unit is arranged so that blanks passing from the slotting machine will be delivered on to the conveyor of the stacking unit. The upper part 2 of the frame overhangs the body

and tapers towards the slotting heads so that the stacker frame will clear the frame and working parts of the slotter. In the end of this tapered part, which may be considered the forward end of the stacker, is arranged 55 a roller 3 which extends transversely of the machine, and other rollers 4, 5, 6, 7 and 8 are transversely arranged in other parts of the frame. Around these rollers is arranged an endless conveyor belt *c*. The roller 4 is 60 spaced horizontally rearward from the roller 3. The roller 6 is adjacent to roller 3, but the top of the roller 6 is a half inch or so higher than the top of the roller 4, and the roller 7 is spaced horizontally rearward from the roller 6. The roller 5 is below and between the rollers 4 and 6, and the roller 8 is lower than the roller 5. Upon the shaft of the roller 4 is provided a sprocket wheel 9 and a sprocket chain 10 connects this wheel with 65 a sprocket wheel 11 on a counter-shaft 12 which is driven by a motor 13.

When the motor is in operation the endless conveyor belt *c* is driven in the direction indicated by the arrows, the roller 4 75 being the driving roller. As shown, the conveyor *c* has a horizontal stretch *c'* from the top of the roller 3 to the top of the roller 4, and from the latter roller the conveyor belt passes downward around the roller 5, thence 80 upwardly over the roller 6, and from the roller 6 it has a horizontal stretch *c''* to the roller 7, this stretch being higher than the stretch *c'*. The conveyor passes downwardly from the roller 7 around the lowermost 85 roller 8 and thence upwardly to the roller 3.

Above the roller 4 is a pressure roller 14, mounted in a pair of swinging arms, one of which is shown at 15 pivotally connected to a bracket 16. The free end of each arm is 90 connected to a vertical rod 17, adjustable in the bracket, which limits the downward movement of the roller, and a spring 18 supplies the yielding pressure necessary to cause the blanks to be frictionally engaged and positively fed rearwardly as they pass between the rollers 14 and 4. A plate 19 is arranged transversely of the machine above and in advance of the roller 6, and at the rear of the roller 14, and this plate forms 95 100

the forward wall of a magazine in which the blanks are stacked. This plate is supported at its ends by arms 20 secured to the brackets 16, only one of the arms being shown in the drawing. The rear wall of the magazine comprises a plate 21 mounted on a carriage 22 which is adjustable back and forth over the rear stretch c^2 of the belt by means of stationary racks, and pinions on the carriage, one rack being shown at 23 and a pinion engaging the rack being shown at 24. The plate 21 is parallel with the plate 19 and extends close to the stretch c^2 of the belt.

In operation, the blanks are fed on to the forward stretch c' of the conveyer belt by the slotter or other machine which operates upon the blanks. The blanks are carried by this stretch between the rollers 14 and 4, one of the blanks d being shown in this position in the drawing. As the stretch c^2 is a little higher than the stretch c , the blank d is delivered edgewise and horizontally against the upwardly traveling part of the conveyer on the roller 6, above the axis of the latter roller, and being forced by the rollers 14 and 4 the blank will pass on to the higher stretch c^2 and its movement will be arrested by the plate 21. This plate is set so that it will stop the blanks before their rear edges reach the top of the roller 6 so that said rear edges will overhang the part of the conveyer which is traveling upwardly on the roller 6. This is illustrated in the drawing, where the rear end of the blank d' and the rear ends of the blanks shown above the blank d' , overhang the upwardly moving part c^2 of the conveyer against which the forward edge of the blank d' is being forced, and overlap the latter blank. Hence when the blank d' moves from the stretch c' on to the stretch c^2 of the conveyer it will raise the blank d' , and those above it and be carried under the blank d' against the plate 21. Thus each blank as it passes from the forward stretch c' on to the rear stretch c^2 of the conveyer will lift the blanks already stacked and pass under them.

The operator removes the stacked blanks from the magazine from time to time as they accumulate and the plate 19 of the magazine is necessary to keep the blanks in order.

As the conveyer belt in the drawing is one continuous piece, of course the two horizontal stretches of the conveyer travel at the same speed, and of course the speed of the conveyer must be regulated to suit the delivery of the blanks from the slotting or other machine which operates upon the blanks. Instead of making the conveyer of one continuous piece of belting it might be made in two parts, each having a horizontal stretch, but that would necessitate additional gearing to make the two stretches travel at the

same speed, and such an arrangement would not be as desirable as that shown.

For stacking blanks of different widths the adjustable stop plate 21 will be set so as to stop the blanks at a point where their rear edges will overhang the face of the roller 6.

What I claim is:

In a stacker for box blanks, an endless conveyer, pairs of horizontally spaced rollers over which said conveyer extends in front and rear stretches, the roller at the front end of the rear stretch being adjacent to and extending slightly above the roller at the rear end of the front stretch, an idle roller below the latter rollers and around which said conveyer extends in passing from the front to the rear stretch, a pressure roller above the front stretch and cooperating with the roller at the rear end thereof to feed the blanks to the rear stretch, and a stop over the rear stretch adapted to arrest the blanks with their rear ends overhanging the front face of the front roller of the rear stretch.

In testimony whereof I affix my signature.

HENRY B. GREENWOOD.
